UNITED STATES PATENT OFFICE.

HERBERT P. H. GALLOWAY, OF TORONTO, CANADA.

TIME CONTROLLING DAMPER MECHANISM.

SPECIFICATION forming part of Letters Patent No. 783,515, dated February 28, 1905.

Application filed January 23, 1904. Serial No. 190,345.

To all whom it may concern:

Be it known that I, HERBERT PETER HOWELL GALLOWAY, of the city of Toronto, in the county of York, in the Province of Ontario, 5 Canada, have invented certain new and useful Improvements in Time Controlling Damper Mechanism, of which the following is a specification.

My invention relates to improvements in furnace-draft-regulating devices; and the object of the invention is to devise a simple automatic device whereby the draft-damper of furnaces may be opened and the check-damper closed at a predetermined time, thereby regulating to a nicety the temperature of a house without the necessity of personal attention at inconvenient periods, as is required at the present time; and it consists, essentially, of a box provided at one end with an alarm-clock, 10 a lever pivoted in the opposite end of the box and having the long end extending inwardly and connected to the bottom of the box by a link extending slightly over the end, said link being connected by a weighted cord to the 15 alarm-hammer of the clock and a cord detachably connected to the short end of the lever outside of the box and having a weight suspended therefrom, such cord extending and being operatively connected to the draft-damper, 20 check-damper, and slide-dampers, the parts being otherwise arranged and constructed in detail as hereinafter more particularly explained.

Figure 1 is a perspective view showing a 25 furnace provided with my equipment. Fig. 2 is an enlarged detail of the operating portion of the equipment.

In the drawings like characters of reference indicate corresponding parts in each figure. 30 A is the furnace, which is provided with the usual bottom draft-damper B, shown closed, the top check-damper C, shown open, and the slide-damper D, shown closed, as indicated.

E is a box suitably supported in the wall of 35 the furnace-room or basement and provided with a transparent front e suitably hinged, so that it may be readily opened.

F is the alarm-clock, located in the box at one end and having the alarm-bell removed therefrom.

f is the vibrating hammer of the alarm-bell.

G is the lever extending through the opposite end of the box to that in which the alarm-bell is located and pivoted on a bracket g.

g' is a ring suspended by a chain or cord g² 55 and through which the lever G extends. The ring g' is designed to limit the downward movement of the lever G.

The lever G is preferably provided with a reduced end g³, and g⁴ is a link connected at 60 one end to the staple at the bottom of the box and the other looped end being arranged to extend over the reduced end g³ of the lever.

2 is a flexible cord which connects the link g⁴ with the hammer F of the alarm-clock. On 65 the cord 2 I provide, preferably, a ring-weight 3, so as to always keep the flexible cord 2 taut.

H is a cord provided with a ring h, which is designed to extend over the short end of the lever G, and H' is a weight which is suspended from the cord H and designed to exert an upward pressure to the long end, so as to hold the upper end of the link securely yet delicately on the extreme reduced end of the lever. The cord H hangs loosely from a pulley I on the ceiling and extends over such pulley, through another pulley, I', thence to the lower end of the damper B. I provide a hook i on the cord for a purpose which will hereinafter appear, and a hook i' I connect 80 through one of the links j of the cord J, which cord extends over a pulley j' on the ceiling and around a pulley j², secured on a standard j³ to the slide-damper D. A branch cord H² is connected to the cord H below the 85 pulley I and extends over one sheaf k of the double pulley K down to a weight K', to which it is securely fastened, thence over the sheaf k' of the double pulley K, to and over the pulley L, attached to the ceiling, and down 90 to the check-damper C. The cord H² is provided with a loop h² for a purpose which will hereinafter appear.

The operation of my device is as follows:

The alarm-clock is first set in the usual way so as to ring at a certain hour in the morning or at any other convenient period. As soon as the first tremor of the hammer starts the link g^4 is drawn off the end of the lever G, and thereby the lever is tilted on its pivot, so as to drop the ring h , and consequently the weight H', which pulls down upon the cord H and raises the damper B. The cord H² at the same time pulls the weight K' upwardly toward the sheaf k of the pulley K, and the cord H² passing over the sheaf k' consequently slackens between the pulley K and the furnace, thus allowing the check-damper to fall. It will be seen that the draft will now be on in full force without any check and that the furnace will burn up briskly. The advantage in this of course will be readily understood to those having to get up early in the morning to attend to the furnace, and especially from the fact that early rising is obviated and the house will be warmed thoroughly before the inmates get up. It will therefore be seen that the furnace may be banked up at night and the rooms kept cool for sleeping, which is an important desideratum. Should it be desired at any time to allow the furnace to burn up for a predetermined length of time, this may also be effected by removing the cord H from the damper B and connecting the hook i to the eye h² in the cord H², in which case the damper C would close the same as the damper B, so that immediately the weight H' falls the damper C would likewise be opened and the draft checked. It will also be understood that where slide-dampers are provided, as indicated at D in the drawings, such slide-dampers may be manipulated simultaneously with the main damper by reason of the connection of the cord J to the main cord H by the hook j extending into one of the links. The amount of movement of the slide-damper may be varied as may be required, depending upon the position that the hook occupies in the links j.

It will be seen from this description that I provide a very simple device, which is not liable to get out of order, for controlling the draft and check dampers of a furnace, which requires but a minimum amount of personal attention. In this specification also it will be seen that I provide a weight on the cord, and this is important, for the reason that it holds the cord always taut and ready for immediate action.

What I claim as my invention is—

1. In a furnace-draft-regulating device, the combination with a suitable clock having a vibrating member, of a lever suitably pivoted, a link connecting the long end of the lever to a rigid support, a flexible cord connecting such link to the vibrating member, and a cord suspended from the short end of the lever and provided with a weight and extending over

suitable guiding pulleys or ways to the damper as and for the purpose specified.

65

2. In a furnace-draft-regulating device, the combination with a suitable clock having a vibrating member, of a lever suitably pivoted, a link connecting the long end of the lever to a rigid support, a flexible cord connecting such link to the vibrating member, and a cord suspended from the short end of the lever and provided with a weight and extending over suitable guiding pulleys or ways to the damper, and a supplemental cord connected to the aforesaid cord and operatively connected to the check-damper, so as to allow such damper to close upon the opening of the draft-damper as and for the purpose specified.

70

3. In a furnace-draft-regulating device, the combination with a suitable clock having a vibrating member, of a lever suitably pivoted, a link connecting the long end of the lever to a rigid support, a flexible cord connecting such link to the vibrating member and a cord suspended from the short end of the lever and provided with a weight and extending over suitable guiding pulleys or ways to the damper, a supplemental cord connected to the aforesaid cord and extending over the sheaf of a pulley and connected to a suitable weight, and passing from such weight upwardly over the other sheaf of the pulley and over suitable guiding-pulleys to the check-damper as and for the purpose specified.

80

85

90

4. In a furnace-draft-regulating device, the combination with a suitable clock having a vibrating member, of a lever suitably pivoted, a link connecting the long end of the lever to a rigid support, a flexible cord connecting such link to the vibrating member and a cord suspended from the short end of the lever and provided with a weight and extending over suitable guiding pulleys or ways to the damper, and a supplemental cord adjustably connected to the main cord and extending over suitable guiding-pulleys to the slide-damper as and for the purpose specified.

95

5. In a furnace-draft-regulating device, the combination with a suitable clock having a vibrating member, of a lever suitably pivoted, a link connecting the long end of the lever to a rigid support, a flexible cord connecting such link to the vibrating member and a cord suspended from the short end of the lever and provided with a weight and extending over suitable guiding pulleys or ways to the damper, a supplemental cord connected to the aforesaid cord and operatively connected to the check-damper, so as to allow such damper to close upon the opening of the draft-damper, and an attaching device, such as a hook secured to the main cord and designed to be suitably connected to the supplemental cord as and for the purpose specified.

100

105

110

115

6. In a furnace-draft-regulating device, the

120

125

combination with a suitable clock having a vibrating member, of a lever suitably pivoted, a link connecting the long end of the lever to a rigid support and flexible cord connecting such link to the vibrating member, a weight hung intermediate of the length of the cord, and a cord suspended from the short end of the le-

ver and provided with a weight and extending over suitable guiding pulleys or ways to the damper as and for the purpose specified. 10
